UNITED STATES PATENT OFFICE.

CHARLES N. JACKSON, OF NEW YORK, N. Y.

COMBINATION LEDGER AND STATEMENT POSTING FORM.

1,262,197.

Specification of Letters Patent. Patented Apr. 9, 1918.

Application filed April 27, 1917. Serial No. 164,835.

To all whom it may concern:

Be it known that I, CHARLES N. JACKSON, a citizen of the United States of America, residing at New York, N. Y., have invented 5 new and useful Combination Ledger and Statement Posting Forms, of which the following is a specification.

My invention relates particularly to a construction for typewriting ledger and 10 statement postings.

It has been customary in the past to attach a statement blank to the front of a ledger sheet with an interposed layer of carbon secured by lateral clips. These 15 clips cause difficulty in feeding the sheets into the machine and readily become detached and the sheets displaced. This old system also results in having the carbon or imprint on the retained ledger sheet 20 which is likely to become blurred by frequent handling. It is my object to avoid these difficulties and provide a simple but inexpensive construction by means of which statements may be simultaneously imprinted 25 on the ledger sheet and on the statement sheet, and by which the same ledger sheet may be used for a considerable period of time and new statements posted from time to time.

30 In its preferred form the invention contemplates a double ledger sheet folded along the upper edge in combination with a carbon sheet interposed between the ledger folds so that the ledger receives the first 35 type or imprint and the carbon is impressed upon the statement sheet. The carbon and statement sheets are preferably supported by a carrier so that they can be readily handled and inserted and removed. A 40 statement sheet is adapted to be adjusted relative to the carrier so as to bring the sheet in its proper relation to the ledger sheet. The carrier and ledger sheets are preferably provided with line indices to assist in location. 45

Figure 1, is a perspective view of forms embodying my invention, one corner of the ledger sheet and one corner of the carbon being broken away to disclose the other 50 parts.

Fig. 2, is a perspective view of the carrier and the carbon and statement sheets, the carbon sheet being partially broken away to disclose the work on the statement 55 sheet.

The two parts 5 and 6 of the ledger sheet

are preferably integrally connected along the folded upper edge 7. Each part of the ledger sheet is preferably provided along its upper edge on both faces with a blank space 60 8 for the name and address of the customer and the credit or page number. The remainder of each face of each ledger sheet is preferably ruled vertically to accommodate the various items which it is customary to enter such for instance, as "Folio," "Date," "Memo," "Charges," "Credits," "Balance" and "Proof." All four faces of the ledger sheet may be used according to my invention so as to furnish in effect a continuous 70 record extending over a period of several months.

The statement sheet 9 is similarly ruled but will usually be only wide enough to include the date, memo charges and credit 75 columns. New statements are usually posted and mailed each month.

The carbon paper or other impression sheet 10 is rectangular in form and has its transfer surface at the rear and it is of 80 sufficient width and length and is so arranged as to overlie the outer face of the statement sheet 9.

The carrier 11 is preferably of a size to substantially fit within the folds of the 85 ledger sheet. The lower edge of the carrier is preferably provided with slits 12, 12 so as to form an intervening cross strip 13 beneath which the lower end of the statement sheet 9 may be drawn and held. The 90 lower end 14 of the statement sheet is preferably folded in back of the carrier so as to assist in holding the statement sheet in place and keep the end out of the way. The upper end 15 of the statement sheet may be 95 folded down when necessary as shown in Fig. 2. The carbon may have a flap 16 pasted or otherwise secured to the carrier. The left-hand edges of the ledger sheet and the carrier are preferably provided with 100 indices or line numbers or marks so as to facilitate locating the heading of the statement sheet on the carrier opposite the blank which is to be filled in on the ledger sheet.

To use the device the parts are assembled 105 as shown in Fig. 1 and inserted in the typewriter in the usual manner. The desired item is then entered on the ledger sheet and simultaneously imprinted on the statement sheet. The folded ledger sheet and statement and carbon are kept together and inserted in the machine and removed from 110

time to time as required. This brings the direct imprint of ink on the ledger sheet which is intended to be permanently retained, whereas, the carbon is impressed on the statement sheet which is of much less relative importance. Whenever it is desired to insert a new statement sheet, the new sheet will be adjusted so as to bring the next ledger item at the top of the statement sheet. 10 This keeps a running account on the ledger sheet but permits new statement sheets to be used from time to time.

Although I have shown the carbon as pasted to the carrier it will be obvious that 15 it may be secured in other suitable ways for instance, in the manner that the statement is secured. Similarly, the statement may be lightly pasted to the carrier at one or more corners so that it can be readily detached. 20 Some advantages of this invention may be had where the carbon and statement sheets are not pasted or otherwise attached to the carrier. In some cases the carbon and statement may be temporarily lightly pasted or 25 otherwise suitably secured directly to the inside of the folded ledger sheet. The carbon may also be temporarily fastened directly to the statement. Also the carrier and statement may be combined and the carbon attached to it direct, to be removed before 30 sending out the statement. It is also possible to provide carbon on the face of the carrier and furnish a transparent statement sheet which will thus be written on the back 35 and can be read from the front.

This contemplates the use of the doubled or folded ledger sheet as a housing so as to protect and hold in place the upper edges of the carbon and statement sheet. Although 40 I prefer that the two parts of the ledger sheet be integral, it is obvious that they might be pasted or otherwise suitably secured together at the upper edge.

I claim:

45 1. A combined ledger and statement posting means comprising a double faced folded ledger sheet, a statement sheet, a carrier for the statement sheet insertible between the folds of the ledger sheet, means for holding 50 the statement sheet in various adjusted positions on the carrier to register with data on the front fold of the ledger sheet and a carbon sheet disposed between the folds of the ledger sheet with its transfer surface against 55 the statement sheet.

2. In a combined ledger and statement posting device, a carrier adapted to be engaged between the folds of a ledger sheet, a carbon sheet fastened at one edge to said 60 carrier and means for holding a statement sheet adjustably engaged on the carrier.

3. The combination of a ledger sheet, with

a separate carrier sheet having an opening, a statement sheet passing through said opening and adjustably secured to the carrier, 65 and a carbon sheet connected with the carrier and movable therewith and interposed between the statement sheet and the ledger sheet, said statement sheet and carbon sheet being operatively associated with the ledger 70 sheet so that the act of writing upon the ledger sheet will produce a carbon impression upon the statement sheet.

4. Combination ledger and statement posting means, comprising a two-leaved ledger sheet with edges connected together at the top, a carrier removably located between the front and rear leaves of the ledger sheet and having two edges corresponding with the edges of the ledger sheet for locating the 80 carrier in proper position between the leaves of the ledger sheet, said carrier having a slit parallel with the top edge of the ledger sheet, a statement sheet having a portion extending from the face of the carrier 85 through said slit to the back of the carrier for locating the statement sheet with relation to the carrier and in proper relation to the ledger sheet and a carbon sheet interposed between the statement sheet and the 90 front leaf of the ledger sheet.

5. The combination of an external double ledger sheet having its two leaves connected together at their top edges and provided along one vertical margin of each page with 95 line indices, a carrier sheet disposed between the front and rear parts of the ledger sheet and positioned thereby, said carrier sheet having a vertical marginal column of line indices corresponding to and in horizontal 100 alinement with the indices of the ledger sheet, a carbon sheet secured along one margin to said carrier sheet, a statement sheet interleaved between said carrier sheet and carbon sheet and means for holding said 105 statement sheet with its writing space in alinement with selected indices on the carrier sheet.

6. The combination of a double ledger sheet having its two leaves connected together at their top edges and provided along one vertical margin of each page with line indices, a carrier sheet disposed between the front and rear leaves of said ledger sheet and provided with a vertical marginal column of line indices corresponding to and in horizontal alinement with the indices on the ledger sheet, a statement sheet on the carrier sheet and a carbon sheet on the carrier sheet interposed between said statement 115 sheet and the back of the front page of the ledger sheet.

CHARLES N. JACKSON.
